UNITED STATES PATENT OFFICE.

DAVID L. WINTERS, OF PHILADELPHIA, PENNSYLVANIA.

SPARK-PLUG TESTER.

1,252,639.

Specification of Letters Patent.

Patented Jan. 8, 1918.

Application filed May 22, 1917. Serial No. 170,234.

To all whom it may concern:

Be it known that I, DAVID L. WINTERS, a citizen of the United States, residing at Philadelphia, in the county of Philadelphia and State of Pennsylvania, have invented certain new and useful Improvements in Spark-Plug Testers, of which the following is a specification.

This invention relates to a spark plug 10 tester and more particularly to a device which may be conveniently carried in one's pocket for the purpose of testing and cleaning spark plugs of various sizes, as well as testing the strength of the battery.

One of the objects of the present invention is to provide a simple and practical device of the above general character which will be inexpensive to manufacture. A further object is to provide a device of the above 20 character which will be reliable and efficient in use and operation.

A further object is to provide a spark plug tester so constructed and arranged as to permit the testing of batteries and 25 strength of the current made thereby. A further object is to provide a spark plug tester in which the spark gap of the plug may be measured. A further object is to provide a plug tester of material which may 30 be used to clean the spark plug electrodes.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof, all as more completely outlined herein.

To enable others skilled in the art so fully to comprehend the underlying features thereof that they embody the same by the numerous modifications in structure and relation 45 contemplated by this invention, drawings depicting a preferred form have been annexed as a part of this disclosure, and in such drawings like characters of reference denote corresponding parts throughout all 50 the views in which—

Figure 1 is a perspective view showing one manner of using the device in testing spark plugs;

Fig. 2 illustrates the manner of cleaning 55 the terminals;

Fig. 3 is a detail sectional view;

Figs. 4 and 5 illustrate the adjustability of the terminals;

Fig. 6 is a perspective view of the device.

Referring now to the drawings in detail 60 and more particularly to Fig. 1, the device is shown in connection with the spark plug of a gasoline engine and shows the manner of testing the same. In this figure, 5 represents the upper part of the cylinder of a 65 gasoline engine provided with a spark plug 6 having a binding post or terminal 7 at the upper part thereof and the usual electrodes 8 and 10 at the bottom within the cylinder.

The device as herein shown employed 70

for testing the spark comprises a body member 11 preferably formed of two thicknesses of emery cloth, sand paper, or the like.

I prefer to use emery cloth for the reasons that it is of insulating material, second, provides a dark back ground to better show

the spark and, third, it has an abrasive surface whereby the terminals may be more easily cleaned as will hereinafter appear.

Between the edges of these members are 80 mounted two pieces of flexible sheet metal or other suitable conducting material 12, extending beyond the periphery of the body member 11 any desired amount. I prefer

that these pieces 12 be made of pliable sheet 85 copper preferably oblong in shape, as indicated by the dotted lines. They are securely held between the two thicknesses of emery

cloth 11, with corners 13 closely adjacent each other and forming a spark gap. These 90

corners may be bent away from each other, as shown in Figs. 4 and 6, to increase the spark gap if so desired. The parts 12 are of

such length as to conveniently contact with opposite parts of any size spark plug and 95 the sharp edges thereof will cut through dirt and grease to make a good contact therewith.

In use and operation an edge of one of the members 12 is placed in contact with the binding post 7 while a corner of the other 100

member 12 is brought into engagement with the cylinder shell or nut holding the spark plug in place.

In this manner circuit is substantially established except for the small spark gap between the corners 13 of the members 12, at which point the spark will

be observed. One or both of the parts 12 may be cut as indicated at 14 to facilitate bending.

The device as herein shown may be conveniently operated as above described for the purpose of testing the spark plug, but it will

be clear that it has other advantages for the emery cloth of which the body of the device is made is highly desirable material for cleaning the adjacent parts of the contacts 5 8 and 10 when the spark plug is removed, as shown in Fig. 2.

It will be noted that this body member is of two thicknesses, that is the right-hand side is merely the two thicknesses of emery 10 cloth and forms one gage, while the other side, where the members 12 are embedded, will constitute a thicker gage, for the purpose of measuring the distance between the terminals 8 and 10 of the spark plugs. It 15 is well known that it is highly desirable to have a uniform distance between the terminals of the several spark plugs, in a motor having a plurality of cylinders whereby the highest efficiency may be obtained.

20 From the above it will be clear that the present invention is directed to a simple, practical and inexpensive device particularly adapted for gaging, cleaning and testing spark plugs and circuits, and it is 25 thought will accomplish, among others, all of the objects and advantages herein set forth.

I realized that considerable variation is possible in the details of construction and 30 arrangement of parts without departing from the spirit of my invention, and I therefore do not intend to limit myself to the specific form shown and described.

Having thus described my invention what 35 I claim as new and desire to secure by Letters Patent is:

1. An article of manufacture comprising a body formed of a plurality of thicknesses of insulating material having flat separated 40 electrodes embedded between and projecting beyond the marginal edges thereof their entire length.

2. An article of manufacture comprising

two sheets of material having a roughened abrasive outer surface between one side edge 45 of which are embedded two pieces of flexible electrical conductors providing a spark gap therebetween.

3. An article of manufacture comprising two thicknesses of insulating material one of 50 which is provided with an abrasive surface, and two spaced electrodes positioned therebetween having portions extending beyond the periphery of said insulating material adapted to be brought into contact with the 55 spaced elements of a spark plug, said device also constituting a gage for spacing and cleaning the terminals of said spark plug.

4. An article of manufacture comprising a double thickness of material having a 60 roughened abrasive outer surface and having one side edge concaved toward the center, two pieces of flexible conducting material associated with said material and spaced apart to form a spark gap, the adjacent ends 65 of said conducting material being angularly disposed with relation to each other whereby they may be bent to increase or diminish the space between them to regulate the length of the spark gap so formed.

5. An article of manufacture comprising a body member of insulating material, and having one end of concave form, and two flat conducting members attached thereto and extending beyond and below the same, 70 with the extended parts thereof adapted to be held against the electrically spaced parts of a spark plug, and the spaced apart inner ends adapted to form a spark gap to test the condition of the same.

In testimony whereof I affix my signature in presence of two witnesses.

DAVID L. WINTERS.
